UNITED STATES PATENT OFFICE.

ANDREW JACKSON STONE, OF WASHINGTON, DISTRICT OF COLUMBIA, ASSIGNOR TO
THE GOVERNMENT OF THE UNITED STATES.

METHOD OF AND APPARATUS FOR DELIVERING TORPEDO ATTACKS FROM AIRCRAFT.

1,379,788.

Specification of Letters Patent. Patented May 31, 1921.

Application filed December 27, 1918. Serial No. 268,560.

To all whom it may concern:

Be it known that I, ANDREW JACKSON STONE, a citizen of the United States, residing at Washington, District of Columbia, have invented new and useful Improvements in Methods of and Apparatus for Delivering Torpedo Attacks from Aircraft, of which the following is a specification.

It has been proposed, in the art of marine warfare, to launch self-propelled or automobile submarine torpedoes from aircraft in attacks against seacraft by lowering the torpedo from the aircraft, as the target is approached, through the medium of a wire or cable, and by severing the cable when the torpedo has been lowered to a proper launching position relative to the water. In this plan means is provided for carrying the torpedo initially close to the plane, for lowering the torpedo upon a wire or cable wound upon a reel, the observer in the plane controlling its descent manually, for causing the torpedo to head in the direction of line of flight of the plane, for advising the observer a short interval before it has reached the water, for severing the cable at the plane, and for automatically freeing the torpedo from the grappling mechanism which carries it when the cable is severed. It also may include means for re-reeling if desired.

It is of great importance, in the plan thus outlined, that the cable shall be severed before the torpedo has encountered any considerable resistance in the water, since such resistance against it while it is still attached to the aircraft by means of the wire or cable might seriously affect the flying of the craft and, indeed, might put it entirely out of control. The means proposed for advising the observer a short interval before the torpedo has reached the water, so that he may guide himself in severing the cable, is in the nature of a so called sounder the end of which hangs below the torpedo itself and which in touching the water causes vibrations to be transmitted to the wire or cable upon which the torpedo is hung. While experience has shown that these vibrations are perceptible to the observer, there is danger that under some conditions it may not be and I, therefore, propose means whereby the torpedo shall be automatically released from the cable when it reaches the water. Not only does my invention introduce this posi-

tive safety feature, but it eliminates the function of severing the cable, thus saving the cable upon the aircraft. This function, which is performed by releasing the torpedo from the lower end of the wire or cable instead of at the plane, may be accomplished either automatically or by hand, and some of the appended claims are drawn broadly enough to cover either method. In either case the possibility of the wire or cable dropping in the water in the vicinity of the torpedo and interfering with its course is eliminated.

A most important point of the present invention is the fact that it eliminates the possibility of the torpedo falling by gravity from any height, in which distance the torpedo might nose into the water and loose its course.

The above and other objects of my invention are obtained in the structure described in the following specification, and illustrated in the attached drawings wherein:

Figure 1 is a diagrammatic view showing my invention with the torpedo in the position immediately before the same is launched;

Fig. 2 is a detail view showing in perspective a portion of the torpedo grappling mechanism;

Fig. 3 is an enlarged detail view of the releasing hook which may be employed, one side of the frame of the hook being broken away for the purpose of illustration; and

Fig. 4 is a view, partly in section, illustrating means associated with the torpedo for relieving shock on the latter when it is released.

Referring to the drawings, the aircraft A, (which for illustrative purposes is disclosed as an aeroplane but which may be a lighter-than-air craft,) is shown as carrying a hoisting drum or windlass 10 upon which is wound a wire or cable 11, to the lower end of which cable is releasably attached, as will be described, an automobile torpedo B. The drum 10 is provided with a brake 10^a so that the torpedo may be controllably lowered, and may, if desired, be associated with a suitable motor 12, so that upon occasion the torpedo may be raised after being lowered. The drum may have a suitable register 13 by which the number of feet of cable paid off from the drum may be measured. As these parts, together with the torpedo B, 110

may be of any suitable type or construction, and I claim no novelty therein, *per se*, they are shown more or less conventionally in the drawings. Secured to the lower end of the cable 11 is a releasing hook C and which is herein shown as having a frame 14 provided with a fixed jaw 15 and a pivoted jaw 16 coöperating, when closed, with the fixed jaw to form a substantially closed eye which releasably receives a ring 17 to which the grappling mechanism D, gripping the torpedo B, is secured. The movable jaw 16 has a latch or finger 18 with which coöperates a pivoted spring pressed trip 19 for maintaining the jaw 16 in closed position.

Secured directly to the cable 11 at a point adjacent the releasing hook is a sounder 20', the free end of which is adapted to be brought into contact with the water to indicate to the aviator by the vibration it then transmits to the cable or wire 11, the position of the bomb with reference to the surface of the water. This sounder preferably comprises a plurality of slidably connected stout sections so that it will not, upon being drawn over the water, become entangled or "balled up" as would a piece of ordinary wire.

For the purpose of automatically releasing the torpedo after it is brought to the correct launching position upon the surface of the water, or if desired, slightly above it, a trail 20 which may be similar in construction to the sounder 20' is connected to the trip 19 of the releasing hook C and upon this trail is provided a cup-shaped member 21 having its concave face disposed toward the torpedo, so that when the cup comes into contact with the water, the movement of the trail is retarded with a jerk, whereupon the trip 19 is pulled and the grappling mechanism D, together with the torpedo B carried thereby, is released. If desired, the sounder 20' may be omitted, in which case 45 the trail would be used as a sounder.

It will be noted that the cup-shaped member 21 near the end of the trail acts with the end of the trail as an indicating device for the pilot or observer showing the relative 50 position of the torpedo with respect to the surface of the water. As the torpedo is lowered, the cup-shaped member which hangs substantially vertically will engage the water and produce vibrations in the suspending cable indicating the predetermined height of the torpedo from the water. Splashes will also be clearly observable 55 before the release in operation takes place, for it is necessary for the cup-shaped anchor at the end of the trail to engage the water with sufficient resistance which can only be done after the torpedo is further lowered and the trail assumes a position more nearly at right angles with respect to 60 the suspending cable.

The torpedo B may be gripped by any suitable device which will release itself from the torpedo upon the releasing action above described, so as not to impede the speed or deflect the course of the torpedo, but for purposes of illustration, this means is shown in the drawings as comprising a plurality of pairs of tongs 22, similar to "ice tongs" which are held in grapping position by the load they carry, the upper arms of these tongs being connected by means of ropes 23 to the ring 17. To hold the tongs in spaced position a rod 24 is passed through the tongs, as most clearly shown in Fig. 2. Obviously, when the ring 17 is released, the tongs open up to release the load.

For the purpose of controlling the train of the torpedo, that is, to maintain the heading thereof in parallelism with the head of flight of the aircraft, the torpedo is provided aft with one or more vanes or fins 25, or these vanes or fins or other directing means may be made part of or carried with the grappling mechanism. As will be readily understood by those familiar with the art, when launching a torpedo, the propelling mechanism therein must be set into operation, and to accomplish this object in the present invention, the torpedo B has a starting lever 26 connected by means of a spring 27 to the torpedo, and coöperating with the rod 24 in such a manner that after the grappling mechanism D is released from the releasing hook C and upon separation of the grappling mechanism and the torpedo B, the lever is moved by the spring 27 and water resistance into armed position.

In Fig. 4 of the drawings, I have illustrated shock absorbing means, which may or may not be used, as desired, for relieving the torpedo of excessive shocks, when the torpedo is released and while this shock absorbing means may be of any suitable type, I have shown the same, for illustrative purposes, as comprising a V or trough like member 28 positioned beneath the torpedo, a plate 29 within the trough and upon which the bottom of the torpedo B rests, and springs 30 between the trough and the plate 29. If desired, the springs 30 115 may be replaced by an air cushion or other resilient means. The jaws of the pairs of tongs 22 grip the sides of the trough. When the torpedo is released from the cable 11, the trough will sink into the water and the springs 30 will, to a large extent, relieve the torpedo of injurious shocks.

In carrying out the method of attack with the apparatus herein described, the cup member 21 is adjusted lengthwise of the trail 20 so that when the cup 21 strikes the surface of the water, the torpedo will be at the desired launching position on the surface of the water, or, if desired, slightly above it. The aviator, upon sighting the 120

target pays out the cable 11 so as to lower the torpedo until the free end of the sounder 20' (or the free end of the trail 20 when used as a sounder because of the omission of the sounder 20') drags upon the surface of the water. The sounder will rise and fall with a vibrating movement, and this vibration is communicated to the wire 11 so that the pilot or observer in the 10 aeroplane may observe it, or, if desired, a suitable mechanism may be placed upon the aircraft which would be responsive to such vibrations of the sounder. The aviator, knowing the length of the sounder and the 15 position of the torpedo with respect thereto, can readily ascertain the distance the torpedo is above the water. While the aeroplane is flying through the air, the head of the torpedo is in the same direction as the 20 aircraft, due to the vanes 25, so that by pointing the aircraft in the direction of the target, the torpedo is properly trained. The aviator proceeds upon his flight at any desired height of which the aeroplane is 25 capable so as to stay out of range of hostile guns, until the torpedo is brought to within such range of the ship that the success of the attack is assured. He will thereupon pay out some of the cable 11, so as to lower 30 the cup 21 into the water, the cup being so positioned on the trailer that the torpedo is in proper launching position when the cup strikes the water. When the cup 21 strikes the water, the water will bank up 35 therein, causing sudden retardation of the cup together with the trail, which will jerk the trip 19 backwardly, thus pulling back the pivoted jaw 16 of the releasing hook and releasing the grappling mechanism D and the torpedo B. The tension upon the 40 ropes 23 having been relieved, the tongs 22 will open and free the torpedo in which action the starting lever 26 of the torpedo is actuated through the spring 27. The spring which holds the trip 19 in engaging 45 position is of such strength that it cannot be overcome by air resistance but will be overpowered by water resistance.

It is to be understood that my invention is susceptible of various modifications and changes which would be within the spirit of the invention without departing from the scope of the following claims.

What I claim is:

1. The method of attack herein described, 55 which consists in suspending a torpedo from an aircraft, transporting the torpedo with the same in close proximity to the surface of the water, indicating to the aviator the relative position of the torpedo with respect to the surface of the water, and automatically releasing the torpedo when it has been brought to the proper launching position relative to the water.

2. The method of attack herein described, 60 which consists in suspending a torpedo from

an aircraft at varying distances beneath the same, flying through the air at any desired elevation with the torpedo in close proximity to the surface of the water, indicating to the aviator the relative position 70 of the torpedo with respect to the surface of the water, lowering the torpedo a predetermined distance when launching the same, and automatically releasing the torpedo when it has been lowered to proper 75 position relative to the water.

3. The method of attack herein described, which consists in suspending a torpedo from an aircraft at varying distances beneath the same, flying through the air at any desired 80 elevation with the torpedo in close proximity to the surface of the water, indicating to the aviator the position of the torpedo relative to its proximity to the surface of the water, lowering the torpedo a predetermined 85 distance when launching the same, and releasing the torpedo when it has been lowered to launching position.

4. The method of attack herein described, which consists in suspending a torpedo from 90 air aircraft, flying through the air at any desired elevation, and thus suspended gradually lowering the torpedo, indicating to the aviator the position of the torpedo relative to the water, training the torpedo, automatically 95 releasing the torpedo when it has been lowered to proper launching position relative to the water and starting the propelling mechanism of said torpedo.

5. The method of attack herein described, 100 which consists in suspending a torpedo from an aircraft, flying at a relatively high elevation, and thus suspended gradually lower the torpedo, indicating to the aviator the position of the torpedo relative to the water, 105 training the torpedo, automatically releasing said torpedo from the suspension means at a point adjacent the torpedo, and relieving the torpedo of shocks as it sinks into the water.

6. In combination, an aircraft, a torpedo, 110 means for suspending the torpedo at varying distances beneath the craft, means for indicating to the aviator the relative position of the torpedo with respect to the surface of the water, and means for automatically releasing the torpedo.

7. In combination, an aircraft, a torpedo, means for suspending the torpedo at varying distances from the aircraft, means for 120 indicating to the aviator the position of the torpedo, and means co-operating with the surface of the water for automatically releasing the torpedo.

8. In combination, an aircraft, a cable 125 carried thereby, means for varying the effective length of the cable, a releasing hook on the end of said cable, grappling mechanism releasably carried by said hook, a torpedo carried by said grappling mechanism, 130

a trailer connected to said hook, and means on the trailer for retarding the same and actuating the hook to release the grappling mechanism and the torpedo carried thereby.

5. 9. In combination, an aircraft, a torpedo, means for suspending the torpedo from the craft, a releasing hook on the lower end of the suspension means for releasably securing the torpedo thereto, a trailer connected to 10 said hook, and a member carried by said trailer adapted by striking the water to jerk said trailer and actuate said hook.

10. In combination, an aircraft, a hoisting drum thereon, a cable carried by said drum, 15 a releasing hook on the end of said cable, grappling mechanism carried by said hook, a torpedo carried by said grappling mechanism, means for starting the torpedo when launched, a trailer connected to said releasing hook, a cup shaped member adjustably carried by said trailer, and a sounder connected to the cable adjacent the hook.

11. In combination, an aircraft, a cable carried thereby, means for varying the effective length of the cable, a releasing hook on the end of said cable, grappling mechanism releasably carried by said hook, a torpedo carried by said grappling mechanism, 25 said grappling mechanism being held in 30 grappling position by the weight of the tor-

pedo therein, a trailer connected to said hook, and means on the trailer for retarding the same and actuating the hook to release the grappling mechanism and the torpedo carried thereby.

35. 12. In combination, an aircraft, a cable carried thereby, means for varying the effective length of the cable, a releasing hook on the end of said cable, grappling mechanism releasably carried by said hook, shock 40 absorbing means carried by said grappling mechanism, a torpedo carried by said shock absorbing means, a trailer connected to said hook, and means on the trailer for retarding the same and actuating the hook to release 45 the grappling mechanism, the shock absorbing means and the torpedo.

13. In combination, an aircraft, a cable carried thereby, means for varying the effective length of the cable, a releasing hook 50 on the end of said cable, grappling mechanism releasably carried by said hook, a shock absorber comprising a V shaped member and resilient means in said member, a torpedo carried by said shock absorber and means 55 for actuating the hook to release the grappling mechanism and parts carried thereby.

Signed at Washington, District of Columbia, this 27th day of December, 1918.

ANDREW JACKSON STONE.
